UNITED STATES PATENT OFFICE.

CHARLES MOORE, OF TRENTON, NEW JERSEY.

IMPROVEMENT IN CHASING-MILLS.

Specification forming part of Letters Patent No. **20,290**, dated May 18, 1858.

To all whom it may concern:

Be it known that I, CHARLES MOORE, of Trenton, in the county of Mercer and State of New Jersey, have invented certain new and useful Improvements in Chasing-Mills for Grinding Reeds and other Articles; and I do hereby declare that the same are described and represented in the following specifications and drawings.

To enable others skilled in the art to make and use my improvements, I will proceed to describe their construction and operation, referring to the drawings, in which the same letters indicate like parts in each of the figures.

Figure 1 is a top view of a chasing-mill with my improvements. Fig. 2 is an elevation of the same. Fig. 3 is a section through the line *z z* of Fig. 1. Fig. 4 is a plan of the bottom of the bed.

The nature of my improvements consist, first, in making a chasing-mill self-feeding automatically and continuously by means of one or more circular troughs which receive the substances to be ground or acted upon and deliver them through spouts onto the bed of the mill under the chasing-wheels; second, in a revolving scraper so constructed, arranged, and operated as to separate automatically and continuously that portion of the material on the bed of the mill which is ground most from that which is ground less and deliver it into the discharge-opening in the bed of the mill, and, lastly, in combining with the above-mentioned automatic continuous self-feeding and self-discharging apparatus a heated bed, so as to heat, grind, mull, and mix the materials fed to the mill automatically at the same time and in one operation without manual labor.

In the accompanying drawings, A is the bed of the mill, made of cast iron, and consists of a circular plate or bottom B, Fig. 4, which should rest on a solid foundation A' of some kind of sufficient strength to support the mill. This bottom B has a hole in the center, surrounded by the hub C, from which a series of partitions D D radiate, extending nearly to the edge except D', which extends to the edge, and there are also a series of partitions D² extending from the edge nearly to the hub C, arranged alternately between

the partitions D D, all of which partitions support the bed A, which rests upon them, and is provided with a hole in the center corresponding with the hub C, and that portion of it which the chasing-wheels E E roll upon is provided with V-shaped scores F F, about one-fourth of an inch deep and three-eighths wide at the end toward the center and three-fourths of an inch wide at the outer end. These scores F F are curved, and cross each other nearly at right angles and form pyramidal-shaped protuberances between themselves which may be brought to a point or nearly to a point, which protuberances are designed to prevent the substances acted upon by the mill from slipping forward under the wheels, so as to escape without being properly acted upon and ground or mulled.

The bed A and bottom B are surrounded by a hoop G, so arranged as to cover the ends of the partitions D² and form a steam-tight joint around the bed and bottom, and make a chamber which is supplied with steam through the hole II in the bottom, and after passing around between the partitions D and D² and heating the bed A uniformly it escapes through the hole II' on the opposite side of the partition D'. The hoop G or a similar one should be made to extend a sufficient distance above the bed A to form a curb G' to prevent the substance ground from falling off the plate as it is swept around by the sweep I', which sweeps or scrapes it into the opening J, through which it falls into the receptacle prepared to receive it. The opening J is made through the bed and bottom, and separated from the steam-chamber by the partition J', and is provided with a door J² to close it. The bed A and bottom B may be cast separately and fitted together, and rims may be cast upon them to answer instead of the hoops above mentioned, which rims may be provided with flanges, so as to bolt them together and make a steam-tight joint; but I have succeeded in making them by casting the bed, partitions, and bottom all in one piece, and shrinking on a stout wrought-iron hoop wide enough to cover the space between the bed and bottom and lap onto each, so that the seams can be calked to make a steam-tight joint.

To make the curb I take a strip of stout sheet-iron, long enough to reach around the

bed, and rivet some hasps to each end on the outside, so that when it is applied to the bed a tapering key can be driven into the hasps, which will draw it so tight around the bed as to fix it firmly in its place without additional fastening. The vertical shaft K should be provided with a pivot at the lower end, fitted to turn in a box in or below the hub C, and the upper end of this shaft should be fitted to turn in a box supported by a girder of the building in which it is operated or by strong frame-work adapted to the purpose, and a gear wheel or pulley should be applied to this shaft at or near the upper end, to which the power may be applied to turn it and operate the mill. The axle K' passes through the shaft K, so as to allow the chasing-wheels E E to accommodate themselves to the thickness of the material being ground under them on the bed A. The chasing-wheels E E turn on the pivots L L of the axle K', and one arm of the axle is longer than the other, so that one wheel will not run exactly in the track of the other. These chasing-wheels may be made of sand or grit stone, bushed with wood or metal, so as to turn freely on the pivots L L as the shaft K is turned to roll them around on the plate or bed A to perform the grinding.

In order to feed the mill continuously and automatically, I make a circular trough N around the shaft K, into which the crushed linseed is fed by a trough to supply the mill, and it passes down through the spout O into the bed A, so as to feed the mill constantly and uniformly, and it is forced out under the stones or chasing-wheels by the scraper P, fastened to the shaft K, so as to be carried around by it. There is another circular trough R around the shaft K, below the trough N, which may be supplied with water by a pipe, and conducted onto the bed A by the pipe S, which water is absorbed by the starchy matter in the crushed linseed as it is ground, mulled, or operated upon while it is hot in chasing-mill. These troughs N and R may be arranged at such distances from the shaft as may be desirable, and the bottoms of these circular troughs may be made to rise spirally in one or both directions from the opening into the spout, so as to deliver the crushed seed uniformly around the bed of the mill. The rods T T are arranged so that they can be traversed in the shaft K to adjust the sweep or scraper I, which is fastened to them, which scraper may be set so as to separate that portion of the prepared pulp which is ground most and worked out by the wheels from that which is ground less at each revolution, and the portion so separated is swept around by the outer arm of the scraper and falls into the opening J mulled, heated, and more perfectly prepared for the press than it has ever been done by any other mill or process. The rear end of the scraper I is set in toward the shaft, so as to scrape the pulp which is not separated as above mentioned.

in toward the center, so that the wheels will pass over it again.

It is found to be a great advantage to mull and temper the crushed seed on a hot plate and supply water at the same time, as the heat promotes the chemical affinity between the water and the starchy portion of the seed, thereby precipitating or releasing more of the oil than any other method. Besides, the oil is far more easily expressed from the pulp than when it is prepared in any other way.

By making the mill automatically self-feeding and automatically self-delivering, the labor of filling and discharging the mill by hand is saved, and the pulp is more uniformly and far better prepared and delivered all ready for the press or for packing, and one man's labor is saved entirely who has heretofore been employed to put in and take out the pulp, supply the water, &c. By making the mill to feed and discharge itself continuously, it may be kept constantly running, and is not required to be stopped to remove the charge ground and supply a new one.

The advantages of heating the bed of the mill with steam are numerous, and may be enumerated as follows: First, it is heated all over with a uniform temperature; secondly, there is no danger of its being heated so hot as to scorch or burn the pulp or dry it by evaporating all the water that is put in with it to moisten the starch; thirdly, the heating is done entirely without manual labor, consequently is not attended with any additional expense; fourthly, the mill is not delayed by stopping to remove the crushed seed, as in the old method; fifthly, the crushed seed is supplied uniformly under the wheels, so that they act upon it to advantage, besides they turn easier than if the crushed seed were spread by hand under them with less uniformity than when it is spread automatically.

With my improvements the mill may run constantly without interruption or delay, and do a far greater amount of work and do it far better, and at the same time dispense with one man's labor.

I believe I have described and represented the improvements which I have made in chasing-mills so as to enable any person skilled in the art to make and use them. I will now state what I desire to secure by Letters Patent to wit:

I claim—

1. Making a chasing-mill self-feeding automatically and continuously by means of one or more circular troughs which receive the substances to be ground or acted upon and deliver them through spouts onto the bed of the mill under the chasing-wheels, substantially as described.

2. The scraper I, so constructed and operated as to separate that portion of the material on the bed of the mill which is ground most automatically and continuously from that which is ground less and deliver it to

the discharge-opening in the bed of the mill, substantially as described.

3. In combination with a continuous automatic self-feeding apparatus or a continuous automatic self-delivering apparatus applied to a chasing-mill, a heated bed, so as to heat, grind, mull, and mix the materials supplied

to the mill automatically or without manual labor at one and the same time, as described.

CHARLES MOORE.
